UNITED STATES PATENT OFFICE.

HARRY P. MACDONALD, OF MONTCLAIR, NEW JERSEY, ASSIGNOR TO THE SNEAD & CO. IRON WORKS, OF JERSEY CITY, NEW JERSEY, A CORPORATION OF NEW JERSEY.

REVERSING MECHANISM FOR ROLL-RAMMING APPARATUS.

1,074,882.

Specification of Letters Patent.

Patented Oct. 7, 1913.

Original application filed January 22, 1912, Serial No. 672,645. Divided and this application filed April 22, 1913. Serial No. 762,898.

To all whom it may concern:

Be it known that I, HARRY P. MACDONALD, a citizen of the United States, residing at Montclair, in the county of Essex and State 5 of New Jersey, have invented certain new and useful Improvements in Reversing Mechanism for Roll-Ramming Apparatus, of which the following is a specification.

This invention has reference to an improved reversing mechanism, and relates 10 particularly to the provision of improved reversing mechanism in roll ramming apparatus, it being a division of my application filed Jan. 22, 1912, bearing Ser. No. 15 672,645. It has for its primary objects the provision of an improved reversing mechanism which is simple in character and effective in operation and in which shocks and strains on the operating parts are reduced 20 to a minimum; the provision of a device of the character described in which binding and sticking of the operating parts is prevented; and the provision of improved reversing mechanism having coöperative relation with respect to means for limiting 25 the movement of the ramming roll positively.

The foregoing together with such other objects as may hereinafter appear or are 30 incident to the invention, I attain by means of a structure which I have illustrated in the accompanying drawings in preferred form. In the drawings

Fig. 1 is a plan view of roll ramming apparatus in which my improved reversing mechanism is embodied; Fig. 2 is a side elevation of a portion of the device shown in Fig. 1; Fig. 3 is a plan view of the reversing mechanism drawn on an enlarged scale and Fig. 40 4 is a side elevation of Fig. 3.

In order that a better understanding may be had of the reversing mechanism and its 45 operation, a brief description of the ramming apparatus will first be given. Referring particularly to Figs. 1 and 2 it will be seen that the ramming apparatus comprises a ramming roll 7 carrying a framework 8 which is provided with a rack 9 driven by the shaft 10 through a pinion 11. The roll 7 is guttered or grooved at 50 each end and rides upon and is supported by the angle-iron tracks 12, the grooves en-

gaging the upright flanges or legs of the angles. The shaft 10 is driven by a motor 13, gearing 14, shaft 15 and gearing 16, all 55 of the driving mechanism being mounted in the carriage or framework 17. The rack 9 is carried directly on the pinion 11 and is maintained in proper position by means of the rollers 18 mounted in plates 18' carried on the shaft 10. By means of this mechanism the roll 7 is reciprocated and passes back and forth along the tracks 12 between which the flask (not shown) is 60 placed.

For controlling the movement of the roll 7 I have provided my improved automatic reversing mechanism which is adapted to reverse the motor 13 through the controller 20 which may be of any preferred form. 70 Referring to Fig. 3, it will be noted that a portion of the end of the driving shaft 10 is screw threaded and is provided with two nuts 21 and 22 which are keyed to the shaft or fastened in any other preferred 75 manner, such nuts constituting two fixed abutments. Mounted on the threaded portion of the shaft between the abutments and having threaded engagement with such portion, is a floating member or nut 23 which 80 is held against rotative movement by means of the rods 24 which have sliding engagement with a pulley or sheave 25 loosely mounted on the shaft 10 and connected to the arm or shaft 26 of the controller 20 85 by the flexible connection 27 comprising a pair of straps preferably composed of leather or other suitable material. The nut 21 is provided with a pair of springs 28 located on opposite sides of the shaft and 90 the nut 22 is similarly provided with spring 28' (see Fig. 4).

The operation of the reversing mechanism is as follows: As the shaft 10 is rotated in a direction to drive the roll forward, the 95 floating nut 23 moves longitudinally on the shaft until it contacts with the springs 28 carried on the abutment 21, this engagement causing the nut 23 to rotate with the shaft. The nut 23 imparts rotative movement to 100 the controller shaft 26 through the rods 24, sheave 25, and connection 27, and the rotation of the shaft 26 operates the controller to reverse the motor and the roll 7 is moved

in the reverse direction. As the motor drives the roll back toward initial position, the nut 23 is moved along the shaft 10 away from the abutment 21 toward the abutment 22 until it comes into contact with the springs 28', at which time the controller is again operated in the manner above described to stop the motor. It will be understood that as the nut 23 moves, the rods 24 slide freely in the sheave 25.

By providing the springs 28 and 28' binding or sticking of the nut 23 to either of the abutments 21 or 22 is prevented, and rotative movement is imparted to the nut 15 without jolting or jarring the controller and without causing strain on the parts thereof, so that breakage of the operative parts is prevented.

It will be observed that springs 29 and 30 are mounted on the framework 17, at substantially opposite ends thereof, and that the rack 9 is provided at each end with a downwardly projecting stop or abutment 31, said abutments being adapted to take 25 against the springs 29 and 30 at the extremes of movement of the roll 7. The springs serve as yielding buffers which stop the movement of the ramming roll and take the strain from off the motor and the driv- 30 ing connections, said springs also serving to assist the motor when the latter is reversed by giving the roll an initial impulse in the reverse direction. The spring buffers also have coöperative relation with 35 the reversing mechanism. The reversing mechanism is actuated substantially at the time when one of the abutments 31 takes against either the spring 29 or the spring 30. The springs yield sufficiently to insure the 40 throwing of the controller, but at the same time stop the roll so that breakage of the reversing mechanism and the controller parts is prevented. This is of particular advantage in connection with the type of 45 reversing mechanism shown wherein the nut 23 comes into contact with two fixed abutments and thereafter rotates with the main operating shaft of the apparatus. The slowing up of the roll by the action of 50 the spring buffers prevents the banging of the nut against the abutments and also prevents the nut from sticking.

In order to operate the controller manually, regardless of the position of the ramming roll, I provide manually operating means comprising a sheave or pulley 32 mounted in brackets 33 and a cable 34 which passes around the sheave 25 and the sheave 32. A hand lever 35 is secured to the cable 60 34. It will be clear that by means of this mechanism the controller may be operated at will.

In some conditions of service, it may be found desirable to have the roll stop at its 65 inmost position instead of being reversed,

in which event the fixed abutments can be so positioned on the shaft that when the spring buffers are engaged by the stops 31, the controller will turn to neutral position and stop the motor instead of reversing it. It will be understood that the term "fixed abutment" does not necessarily define an abutment rigidly and immovably carried by the shaft, the word "fixed" having reference primarily to the relation between the floating member and the abutments. The latter are fixed relative to the former.

What I claim is:

1. An automatic control mechanism comprising in combination with a driven shaft 80 and a motor for turning the shaft, a fixed abutment carried on the driven shaft, a movable abutment adapted to contact with the fixed abutment, means whereby the rotation of the shaft moves the movable abutment, a controller for the motor, a yielding member between the abutments, and an operative connection between the movable abutment and the controller.

2. An automatic reversing mechanism 90 comprising in combination a threaded driving shaft and a motor for turning the shaft, a controller, an operating shaft for the controller, a pair of spring abutments on the driving shaft, a floating member on the threaded portion of the driving shaft and adapted to contact with the abutments, and a connection between the floating member and the controller shaft.

3. An automatic reversing mechanism 100 comprising in combination with a threaded driving shaft and a motor for turning the shaft, a controller, an operating shaft for the controller, a pair of abutments on the driving shaft, a floating member on the threaded portion of the driving shaft and adapted to contact with the abutments, and a flexible connection between the floating member and the controller shaft.

4. An automatic control mechanism comprising in combination with a driven shaft 110 and a motor, a fixed abutment on the driven shaft and rotatable therewith, a movable abutment adapted to contact with the fixed abutment, one of said abutments having a 115 yielding engagement means, a controller for the motor, means whereby the rotation of the shaft moves the movable abutment, and operative connection between the movable abutment and the controller.

5. An automatic reversing mechanism comprising in combination with a threaded driving shaft and a motor for turning said shaft, a controller, an operating shaft for the controller, a relatively fixed abutment 125 rotating with the shaft, a floating member on the threaded portion of the driving shaft adapted to contact with the fixed abutment, a second member loosely mounted on the shaft, a connection between said second 130

member and the controller shaft, and a slip connection between the floating member and the second member whereby the floating member is free to move longitudinally of the shaft but is prevented from rotating therewith until it engages with the fixed abutment.

In testimony whereof I have hereunto signed my name in the presence of the two subscribed witnesses.

HARRY P. MACDONALD.
